QUANTITY INDICATOR FOR LIQUIDS

James MacCallum, Jr., St. Louis, Mo.

Application May 27, 1920, Serial No. 384,632

6 Claims. (Cl. 73—30.3)

This invention relates to improvement in quantity indicators for liquids, and has for its primary object an indicator so constructed and operated that the quantity of liquid in the container can be seen at a glance without the necessity of introducing a measuring stick into the container.

A further object is to construct a quantity indicator for liquids which has a submerged compression chamber in such a manner that the volume of air in the compression chamber, which is absorbed by the liquid or varied by any other cause, may be maintained and thus cause the indicator to work and register properly by maintaining a constant working head at all times.

A still further object is to construct a quantity indicator for liquids in such a manner that air absorbed from the air pressure chamber is replaced by delivering additional air to the pressure chamber without draining the entire liquid container.

In the drawings:

Fig. 1 is a vertical sectional view of a liquid container with my device in position, and showing a portion thereof in section.

Fig. 2 is an enlarged vertical sectional view of the air or compression chamber with parts broken away.

Fig. 3 is a top plan view of the air compression chamber.

Fig. 4 is a similar view with the housing or top of the chamber removed.

Fig. 5 is a fragmental section of a portion of the container, showing a modified form of construction.

Fig. 6 is a view partly in section and parts broken away showing one form of suction device.

In the construction of my device 5 represents a liquid container. This may be of any desired shape or construction, and is provided with a screw threaded neck 6, and a closing cap 7. This cap is provided with the vent 8 so as to admit air to the container so that liquid can be withdrawn.

In the bottom 9 of the container, I form an opening 10 through which is inserted a portion of the ring 11, the portion 12 of the ring extending into the tank and forming a sediment trap. Extending from the portion 12 of the ring is a right angular projection 13, which is screw threaded as at 14. The portion 15 of the right angular projection is turned inward and is adapted to act as a bearing surface for the flange or edge 16. Formed integral with this

flange 16 is a cup shaped member 17, which extends upwardly and into the container. This cup 17 is provided on its sides with a plurality of flutes or outwardly pressed portions 18. These portions are spaced apart as shown in Figs. 3 and 4 and leave the remaining edge 19 of the cup of the same diameter as the top of the casing 20 of the air pressure chamber 21. This air pressure chamber is provided with a concave or dish-shaped bottom 22, which has a central depression 23. This depression is provided with openings 24 through which air and liquid may enter the air pressure chamber. The bottom is also provided with a central opening 25 through which the end 10 of the pipe fitting 27 projects. This fitting may be used for withdrawing the liquid from the container by gravity, or it may be used as a fitting to which may be attached various kinds of pumps and suction devices for withdrawing the liquid.

15 Formed integral with the flange 16 is a flanged projection 28, the flange of which is screw threaded as at 29. These screw threads are adapted to receive the fitting 27. Secured between the cup 17 and the flange member 28 is a convex shield or baffle 30, the purpose of which is to deflect air bubbles toward the center and toward the projection 26 formed on the fitting 27. The cup shaped member 17 and the shield or baffle 30 are provided with openings 31, which 20 register with each other and communicate directly with the interior of the container.

25 Passing through one of the openings is a tube 32 which extends to a point near the top of the tank, and is for the purpose of introducing air beneath the baffle 30. Secured within the 30 top of the housing 20 is a pipe 32a, which pipe extends upwardly and is secured in a fitting 33, which in turn extends through the wall of the tank or container 5, and is held in position by 35 means of a lock nut 34. To this fitting is secured a pipe 35, which has a gauge or indicator 36 secured to its opposite end. This gauge is 40 adapted to indicate the amount of pressure contained in the chamber 21 and thus designate the amount of liquid in the container.

45 It is to be understood that the gauge 36 may be placed at any convenient place, or at any desired distance from the tank.

The fitting 27 is provided with a passageway 37, which communicates with the tank at a point located beneath the baffle 30 by means of a port 38, and the outer end 39 of the fitting is so arranged as to enable a suction line 51 to be connected thereto which line is in turn

connected to a conventional vacuum tank or other intermittent suction device 52.

It will be seen by reference to Figs. 1 and 2 that the opening 38 through which the liquid within the container 5 is withdrawn is in such proximity to the end of the tube 32, that supplies the air employed to replenish the pressure chamber 21 therewith, that there is a commingling of such delivered air with the liquid drawn through the opening 38 and the conduit 37, upon the periodic withdrawal of liquid incident to the working of the apparatus. The result is, as is demonstrated in the practice of this invention, that upon a cessation of such liquid withdrawal the air that is commingled with the liquid withdrawn and which is in the fitting 27 and the conduit 37 passes back through the opening 38, whence it is directed so as to be available for and utilized in maintaining the desired volume of air within the chamber 21.

The operation of my device is, as follows:

After all of the connections have been made and tightened the liquid is introduced into the container. This will gradually rise in the tank and will also flow through the openings 31, 40 and 24, as well as through the flutes formed in the cup 17. This will commence to compress the air in the chamber 21 above the liquid, and in turn this pressure of air will be transferred to the gauge. Ordinarily the liquid poured into the container rises to any level A Fig. 1. A portion of the liquid will enter the pressure chamber 21 as stated above and rise to a level B, such that the air pressure in the chamber just balances the hydrostatic head of the liquid in the tank. When the liquid is withdrawn through the fitting 27 then the space beneath the baffle 30 of the air pressure chamber empties as does the pipe 32. The openings 31 are so graduated in proportion to the inside diameter of the pipe 32, that air will flow through the pipe faster than the liquid flows through the openings 31 and the opening 40 to take place of the liquid withdrawn. This air rises upward and into the pressure chamber, and in event that the volume of air in the chamber has been reduced by any cause whatever, it is replaced, and the balance of the air escapes from the underside of the air pressure chamber through the flutes 18 and through the liquid to the top of the container, thus maintaining a constant working head.

If the liquid is withdrawn through the fitting 27 faster than it can be replaced by flow through the openings 31 and 40 a temporary partial vacuum is set up beneath the shield 30. This will cause air to be drawn through the pipe 32 and discharged beneath the shield 30. This air will then rise upward when the liquid, which has been withdrawn, is replaced from the tank and come in contact with the under surface of the shield 30, which will direct it toward the portion 26 of the fitting 27, the shield 30 being provided with the opening 40, which is slightly larger than the portion 26, will allow the air to pass upward and lodge against the bottom 22 of the chamber 21. This bottom being concaved will act as an air trap, and when sufficient air has lodged against the bottom 22 to displace enough liquid to uncover the openings 24, the air will pass upward and into the chamber 21.

I have found from experience that liquids, especially gasoline, will absorb air and in a pressure chamber of my construction, were this air not replaced, the chamber would gradually fill

up with gasoline and the device rendered useless, and this would necessitate the removal of the fitting 27, and the complete draining of the tank or the container 5 in order to re-establish the balance of pressure required.

The cup 17 is made small enough so that by the removal of the securing ring 41 the pressure chamber and its component parts can be removed from the container, it being necessary however first to remove the pipe 35 and the lock nut 34.

I may, if desired, extend the pipe 32 up through the top of the tank. It is necessary that a constant volume of air be maintained in the pressure chamber so that the working head or liquid level within the chamber can be maintained to exert pressure against this volume of air. If the volume of air is varied, that is reduced, the liquid will rise in the air pressure chamber and the weight of this additional liquid will act against the working head of the liquid in the tank and cause an error in the indication of the gauge. If the volume of air in the pressure chamber is not maintained constant by air replacement, the working head will vary and the gauge will not register accurately as pointed out above.

By the use of my device, this working level or head and the air volume in the pressure chamber is always maintained constant by the automatic supply of additional air beneath the chamber, and when the volume of air therein increases, as is the case when the air expands due to a rise in temperature or any other cause, the air can pass out through the openings 23 and 24 in the concave bottom of the pressure chamber and into the liquid container thus restoring the working head of the liquid against the air in the pressure chamber. During the withdrawal of the liquid the air in the pipe connection between the tank and the suction device or pump obviously becomes mixed with the liquid while it passes therethrough and when the vacuum or suction ceases to operate the mixed air and liquid in this connection returns by gravity to the liquid container through the passages 37 and 38 in the fitting 27, and the entrapped air then rises upward through the liquid and passes through the passageways 40. A certain amount of this air also enters the pressure chamber through the passageways 23 and 24, thus maintaining the volume of air in the chamber constant.

Having fully described my invention, what I claim is:

1. A quantity indicating device for a liquid container comprising an air pressure chamber having a perforated bottom, said chamber being located in and communicating with the liquid at the full depth to be measured, means through which liquid may be withdrawn from a place beneath said chamber, means for restricting the replacement of liquid from said container to said place thereby creating a partial vacuum thereat during the withdrawal of liquid, means for conducting air to said place as a result of the vacuum thereat, the air upon cessation of the liquid flow being transferred to the chamber, a gauge located without the container, and a pipe connection between the air pressure chamber and the gauge.

2. A quantity indicator comprising a liquid container having an opening formed in the bottom thereof, a screw threaded ring secured to said container and encircling said opening, an air

pressure chamber having a concave perforated bottom, a downwardly concave baffle located beneath said bottom, means carried by the ring for securing the air pressure chamber and baffle thereto and within the container, means for creating a suction beneath said baffle, means for conducting and releasing air beneath said baffle as a result of said suction, said air adapted to rise upward and pass through the perforated bottom, a pressure gauge located without the container, and a hollow connection secured to the air pressure chamber and in communication with the interior thereof and extending to the gauge for conveying the container pressure to the gauge.

3. A quantity indicating device comprising a container having an opening in its bottom, a flanged screw threaded ring secured to the container around said opening, a second screw threaded flanged ring adapted to be screwed to the first mentioned ring, a fluted cup extending upwardly within the container, said cup having its bottom flanged and secured between the screw threaded rings, a deflecting shield carried by the flanged bottom of said cup, said cup and shield having openings formed therein and adapted to permit the passage of liquid from the container to the underside of the shield, an air pressure chamber having a concave perforated bottom secured within the cup above the shield, an air pressure pipe secured to the air pressure chamber and communicating with the interior thereof, said air pressure pipe extending through one of the walls of the container, a gauge located outside the container and secured to said air pressure pipe, an air supply pipe having its one end secured through the wall of the cup and beneath the shield located in said container, its opposite end terminating near the top of the container, and a pipe fitting secured to the bottom of the cup for the purpose of withdrawing liquid from the container.

4. A quantity indicating device for a liquid container wherein the surface of the liquid is open to atmospheric pressure whatever be the level of such surface, comprising a pressure chamber communicating with the liquid at the full depth to be measured, a gauge, a pipe connecting said gauge and pressure chamber, a sec-

ond pipe having its lower end immersed in the liquid and terminating below said chamber, its upper end being above the normal liquid level, means through which liquid may be withdrawn

5 from a point beneath said chamber, means for restricting the flow of liquid to said point thereby creating a partial vacuum beneath the pressure chamber and uncovering the immersed end of said second pipe whereby air can pass therefrom and be delivered and trapped beneath said pressure chamber and be directed to said chamber.

6. A quantity indicating device for liquids comprising a pressure chamber immersed in and

15 communicating with a liquid at the full depth to be measured, a gauge, a pipe connecting said gauge and pressure chamber, a second pipe having its upper end open to atmosphere and having its lower end immersed in the liquid and below the pressure chamber for conducting free

20 air thereto, means through which liquid may be withdrawn from beneath said pressure chamber, means for restricting the flow of liquid from the container to beneath the pressure chamber thereby creating a partial vacuum and uncovering

25 the immersed end of said pipe and drawing air therefrom, said air adapted to be transferred to the pressure chamber.

6. A quantity indicating device for a liquid

30 container comprising an air chamber in communication with the liquid at the full depth to be measured, a second chamber provided with an aperture for communication with said air chamber below the liquid level therein and being apertured for communication with the liquid in

35 the container and adapted to receive and hold liquid therefrom, means through which liquid may be intermittently withdrawn from the second chamber, means for restricting the flow of liquid from said container to said second chamber thereby intermittently creating a partial

40 vacuum therein, means for conducting air into said second mentioned chamber as a result of said vacuum, said air then passing into the air chamber, an indicating gauge, and a pipe in communication with said pressure chamber and gauge.

JAMES MACCALLUM, JR.
